UNITED STATES PATENT OFFICE.

DANIEL HERMAN KLEINSCHMIDT, OF BUFFALO, NEW YORK.

EXERCISING-MACHINE OR GAMING APPARATUS.

1,105,329.

Specification of Letters Patent. Patented July 28, 1914.

Application filed January 17, 1914. Serial No. 812,711.

To all whom it may concern:

Be it known that I, DANIEL HERMAN KLEINSCHMIDT, a citizen of the United States, residing at Buffalo, in the county of Erie and State of New York, have invented certain new and useful Improvements in Exercising-Machines or Gaming Apparatus, of which the following is a specification.

This invention relates to improvements in exercising machines or gaming apparatus designed for automatically registering the force of a blow applied with a baseball bat, or other similar object.

The primary object of my invention is to introduce into a gaming apparatus the two essential elements of a baseball game; namely, a bat, and a ball adapted to be given a forcible blow with the bat; both being associated with a power registering or indicating mechanism adapted to indicate what the force of the blow imparted to the ball with the bat would result in at the game of baseball.

Another object of my invention is to construct an apparatus of this type in which simplicity, durability and reliability are the essential features, the registering or indicating mechanism of the apparatus being capable of adjustment to differently indicate the force of the blows directed against the ball.

A further object is to improve on gaming apparatus in which the force of a blow directed against a movable portion of the apparatus is registered.

With these objects in view, the invention consists in the novel features of construction, and in the arrangement and combination of parts to be hereinafter described and more particularly pointed out in the subjoined claims.

In the drawings,—Figure 1 is a front elevation of my improved apparatus. Fig. 2 is a plan view of the same. Fig. 3 is an end view. Fig. 4 is a central vertical section taken on line 4—4, Fig. 1. Fig. 5 is an enlarged vertical section taken on line 5—5, Fig. 3. Fig. 6 is an enlarged vertical section taken on line 6—6, Fig. 1. Fig. 7 is a section taken on line 7—7, Fig. 6.

Referring now to the drawings in detail, like numerals of reference refer to similar parts in the several views.

The reference numeral 10 designates the frame work of the apparatus, which may be

variously constructed, but in preferred form 55 comprises a base 11 consisting of longitudinal members 12 and cross members 13 tying said longitudinal members together. Rising from this base are four posts or standards 14 which support a table-like structure 15 60 on which the registering or indicating mechanism and the regulating mechanism are located.

16 are diagonal braces connecting the base 11 and table 15 together at the rear of the 65 frame. The table 15 has at its front edge a vertical portion 17 to which is secured a disk 18 divided on its face into a series of spaces 19. In these spaces is painted or otherwise marked, terms used in a baseball 70 game, such as indicate the force of a blow directed against the baseball when pitched, and the distance the ball safely travels when hit.

Passing through the vertical portion 17 75 and the disk 18 is a spindle 20 which is journaled in said vertical portion and disk and also in a bearing 21 secured to the table 15. To the front end of said spindle is secured an indicating finger 22 and between 80 said vertical portion and the bearing 21 a pinion 23 is keyed or otherwise secured to said spindle. Said spindle is in mesh with a gear wheel 24 secured in any suitable manner to a shaft 25 suitably journaled in bearings 26 and having near its rear end a cable sheave 27 fastened thereon.

28 represents a cable which is secured at one end to a clevis 29 fastened to the base 12 of the frame work; or it may be otherwise suitably secured to said base. From said clevis the cable is directed upwardly in a vertical plane and passes around the cable sheave 27 and thence laterally to a regulating device 30, to a part of which it is secured. Said regulating device is attached to the table 15 and comprises a cylinder 31 having securing flanges 32 provided with slots 33. Through said slots are passed bolts 34 that take into the table 15. The 100 cylinder is provided with removable heads 35 which are preferably threaded thereon, one of said heads having an internal square depression 36 in which fits the square head of a bolt 37 that is secured to a bracket 38 fastened to the table 15. The bolt has 105 threaded thereon a nut 39 by means of which the cylinder 31 may be moved lengthwise on

the table. Within the cylinder is a coil spring 40 bearing at one end against a plate or washer 41 secured to a rod 42 passing centrally through said coil spring and extending out through one of the heads 35, said rod having the cable 28 secured thereto. By tightening upon the nut 39, after loosening the bolts 34, the cylinder 32 will be moved toward the bracket 38, thereby compressing the coil spring 42 within the cylinder and increasing the resistance placed against the force of the blow directed against a spherical element 43 secured to the vertically-disposed portion of the cable 28, said element representing a baseball. After adjustment of the cylinder, the bolts 34 may be tightened to secure the same in position. If it is desired to diminish the tension of the coil spring 42, the nut 39 on the bolt 37 may be loosened and the cylinder moved on the table in an opposite direction so as to permit the spring to expand, thus decreasing the tension placed on the cable.

The indicating finger 22 is normally positioned between the two lowermost spaces 19 on the disk, such point representing zero. In registering the force of the blow directed against the ball 43, the indicating finger is caused to travel to the left in Fig. 1, and the spaces are therefore successively marked in the same direction, the first space being designated "Foul"; the second, "Bunt"; the third, "Base hit"; the fourth, "Two-base hit"; the fifth, "Three-base hit," and the sixth, "Home run." If, in striking the ball 43 with the bat, a weak blow is directed against said ball, the indicating finger would be moved to the left a distance to possibly not exceed a movement confined within the space designated "Foul," and this travel or movement of the indicating finger is increased to bring the same into the other spaces of the series accordingly, as the power of the blow directed against the ball is increased. When the indicating finger 22 passes into the "Home run" space, it engages a trip 44 which projects from the disk 18, and this trip forms part of actuating mechanism 45 adapted to ring an alarm 46 provided on the rear side of the vertical portion 17 of the table. The force of the blow directed against the ball causes the cable 28 to be deflected laterally, as shown in dotted lines in Fig. 1, such movement causing the cable sheave 27 to rotate the shaft 25, which in turn through the medium of the gear wheel 24 and pinion 23 causes rotation of the spindle 20 to which the indicating finger is attached, and consequently causes movement of the indicating finger in a circular or parti-circular path.

In order that the ball 43 is struck by a blow directed in a horizontal or substantially horizontal plane, a guard 47 is pro-

vided directly above the ball, otherwise it would be possible to direct the bat against the ball in a somewhat downwardly inclined direction, which would have a tendency to cause greater pull on the cable against the action of the spring 42, it being clear that the greater the pull on the cable over the sheave 27 the greater will be the movement of the indicating finger.

The ball 43 comprises a two part core 48 having opposite ends threaded, as at 49, the core having an axial bore 50 provided with an enlargement 51 between its ends. This two part core is placed over the cable, and a knot 52 is formed on the cable, or some other enlargement provided in lieu of the other suitable material capable of within the enlarged portion of the bore 50. Nuts 53 of any suitable material are threaded onto the threaded end portions of the core, and between these nuts are placed a series of disks 54, the disks being gradually enlarged from the nuts 53 toward the horizontal center of the ball, as clearly shown in Fig. 6. These disks are preferably made of rawhide, but may be constructed of any other suitable material capable of withstanding the wear and force of the blows directed thereagainst. When the ball is thus applied to the cable, it may be fastened in place by pouring molten lead or other metal into the bore of the core, as clearly shown.

Having thus described my invention, what I claim is,—

1. An apparatus of the kind described, comprising a support, a spring carried by said support, an indicating device including a cable sheave, a cable passing around said sheave having one end secured to said spring and its other end secured to said support, and a spherical element secured to said cable.

2. An apparatus of the kind described, comprising a support, an indicating device on said support, a cylinder adjustable on said support, a coil spring within said cylinder, a rod passing through said coil spring and extending from one end of said cylinder, said spring bearing at one end against said end of said cylinder and being confined against expansive movement by said rod, a cable passing around said sheave and having one end secured to said rod and its other end fixedly attached to said support, and a ball secured to said cable.

3. An apparatus of the kind described, comprising a support having a table, a cylinder lengthwise adjustable on said table, a coil spring within said cylinder, a rod passing through said spring and having a washer at one end bearing against one end of said spring, said spring bearing at its other end against one head of said cylinder and said rod extending through said head, a cable operatively connected with the indicating device and having one end secured to said rod

and its other end secured to a fixed point beneath said table, and a ball secured to said cable.

4. An apparatus of the kind described, comprising a support having a table, a bracket secured to said table, a cylinder adjustably secured to said table in a manner to be movable toward and from said bracket, a bolt extending from one end of said cylinder passing through said bracket, a nut applied to said bolt and bearing against said bracket, a coil spring within said cylinder, a rod passing through said coil spring serving to retain the same in a compressed state, said rod extending through the opposite end of said cylinder, an indicating device supported by said table, a cable operatively connected with said indicating device and having one end secured to said rod and its other end secured to a fixed point beneath said table, and a ball secured to said table.

5. An apparatus of the kind described, comprising a support having a base, uprights rising from said base and a table secured to the upper ends of said uprights, a cable sheave mounted on said table, a cable passing over said sheave and extending downwardly for connection at one end with said base, said cable being directed laterally from said sheave for yielding connection at its other end to said table, a ball secured to the downwardly extending portion of said cable and adapted to receive a blow from a baseball bat, a disk applied to the side of said table and divided into a series of spaces, said spaces bearing terms of the game of baseball indicating the force of a blow directed against the ball on said cable, an in-

dicating finger movable over said series of spaces, and operative connection between 40 said indicating finger and said cable sheave.

6. An apparatus of the kind described, comprising a support having a base, uprights rising from said base and a table supported by said uprights and provided at its front edge with a vertical portion, a disk secured to said vertical portion and divided into a circular series of spaces, a shaft passing axially through said disk, a pinion on said shaft, an indicating finger on said shaft 50 adapted to move over said series of spaces, a second shaft, a gear wheel on said second shaft in mesh with said pinion, a cable sheave also on said second shaft, a cable passing over said sheave and having one end 55 yieldingly attached to said support and its other end fixedly attached, and a spherical element secured to said cable.

7. An apparatus of the kind described, comprising a support, an indicating device 60 on said support, a cable having a portion vertically directed and having one end secured to a fixed point of said support and its other end yieldingly secured to said support, operative connection between said cable and 65 said indicating device, a ball secured to the vertical portion of said cable, and a guard secured to said support directly above said ball.

In testimony whereof I affix my signature 70 in presence of two witnesses.
